UNITED STATES PATENT OFFICE.

LYNN A. WILLIAMS, OF EVANSTON, ILLINOIS, ASSIGNOR, BY MESNE ASSIGNMENTS,
TO WILLIAM R. HEATH, OF BUFFALO, NEW YORK.

ACCOUNTING SYSTEM.

1,084,685.

Specification of Letters Patent. Patented Jan. 20, 1914.

Application filed February 11, 1909. Serial No. 477,366.

To all whom it may concern:

Be it known that I, LYNN A. WILLIAMS, a citizen of the United States, residing at Evanston, in the county of Cook and State 5 of Illinois, have invented a certain new and useful Improvement in Accounting Systems, of which the following is a full, clear, concise, and exact description, reference being had to the accompanying drawings, 10 forming a part of this specification.

My invention relates to an improvement in accounting systems and has special reference to a method whereby, when there is a mechanical system for accounting for a workman's wages, a waste-wage register will be actuated when he is not employed on a specific job, and on being assigned to a job the actuation of the waste-wage register ceases at the instant when the actuation of the job- 20 register begins.

The most satisfactory method of accomplishing the result analogous to that described above has been according to the system outlined in my copending application 25 Serial No. 474,323, where an electro-mechanical system is used. A plug seat switch is employed, whereby when the plug is in its normal position an electrical connection is made in such manner that a waste-wage register 30 is brought into the same circuit with a wage-register, and the two are actuated at the same rate. Associated with the wage-registers and the waste-wage registers is a series of job-registers actuated by electro- 35 mechanical means. When a plug is withdrawn from its plug seat and inserted in a jack associated with any given job-register, the actuating mechanism for said register is brought into circuit with the actuating 40 mechanism for the wage-register of any individual workman. On withdrawing the plug from its plug seat, the circuit with the waste-wage register is broken. It is therefore evident that the waste-wage register 45 and the job-register cannot be actuated at the same time. If, when the plug is withdrawn from the plug seat, it is not inserted immediately in the jack associated with any job-register, neither the waste wage register 50 nor the job-register will be actuated, although, of course, the actuation of the wage-register continues.

My present invention is adapted to obviate this difficulty. Associated with each waste-wage register is a switch, which in its nor-

mal position makes connection with a circuit in which the wage-register of any given workman is included. Associated with this switch is an electromagnet, which on being energized attracts the switch, which acts as 60 an armature, thereby breaking the circuit with the actuating mechanism for the waste-wage register. Each workman has a plug supplied with suitable conductors in such manner that on insertion in a jack associated 65 with any job-register, the actuating mechanism of such register is brought into the same circuit with his wage-register. At the same time the insertion of the plug actuates the electromagnet associated with the switch 70 which is adapted to include the waste-wage register in the same circuit, and by such energization the switch is attracted, thereby breaking such circuit. It now becomes clear 75 that the possible difficulty mentioned in connection with my copending application, Serial No. 474,323, is entirely overcome in the present invention, as it is quite impossible that the waste-wage register associated with any wage-register should be thrown out of the 80 circuit until the very instant that a job-register is included in the circuit. The exact manner in which this result is accomplished will be described in detail hereafter.

In the accompanying drawings, Figure 1 85 is a diagrammatic representation of one embodiment of my system; Fig. 2 is a modified arrangement of the system, the totalizing arrangements being for the sake of clearness omitted; Fig. 3 illustrates a suitable form 90 of electromagnetic register-actuating mechanism, and Fig. 4 shows a suitable form of differential gearing that may be used when it is desired to totalize the actuations of certain registers. Fig. 5 shows in a diagrammatic view a means for causing impulses of 95 current flow at different rates in accordance with the application above referred to.

Referring first to Fig. 1, 1 is a battery grounded at 2, and having associated with 100 its terminals the busses 3 and 4. The conductors 5 and 6 act as sources for electrical impulses of predetermined rates and may be connected, preferably in series, to wage-registers A and B, respectively. Each workman has a conductor, as 5 or 6, but for the sake of simplicity, in the present drawing the conductors for only two workmen are shown. The current coming through the conductor 5 goes to the point 9. At the 110

point 9 is placed a switch blade 10, which is held in its normal position by a spring 11, contact being made with the conductor 12 at the point 13. The current flowing through the conductor 12 actuates the electromagnetic mechanism associated with the waste-wage register WA, and then flows through the conductor 14 to the wire 15, and then to ground 16^a. Associated with the switch blade 10 is an electromagnet 7, one terminal of which is connected through the wire 8 with the bus 3. The other terminal is connected through the wire 29 to the sleeve of the plug a. Connected to the tip of the plug a is the conductor 30, which terminates in the contact 31. Connected with the sleeve contact of the jack 32 is the conductor 33, which leads to the conductor 26, which in turn connects with the bus 4 at the point 27. The tip contact of the jack 32 has connected therewith the conductor 34, which leads to the job-register J', the circuit for which is completed through the conductor 35 which leads to the ground 16^a through the conductor 15. The electromagnet 7', which is associated with the workman who has been assigned to register B, controls the circuit connections for the register B in the same way that the electromagnet 7 controls the circuit connections for the register A, and the parts associated with the electromagnet 7' are numbered the same as the corresponding parts associated with the electromagnet 7, except that the numbers are primed. Further description, therefore, of the associated parts of the electromagnet 7' will not be necessary. It will be observed that the plug a associated with the electromagnet 7 and assigned to workman No. 1, let us say, is in the "out" position. When workman No. 1—that is, the workman who is assigned to the wage-register A—registers "in" and his plug a remains in the "out" position, as would be the case when the workman is not assigned to any particular job, the circuit through the register A will be closed across the switch contact 10 through the waste-register WA, as previously described. Let us now suppose that workman No. 2, who is assigned to wage-register B, has registered "in" and is assigned to some particular job so that the plug b is plugged into the jack 18. Current will then flow from the battery 1, conductor 3, conductor 22, through the winding of the electromagnet 7', conductor 24, the sleeve of plug b, the sleeve contact of the jack 18, conductor 25, conductor 26, and back to the battery through conductor 4. The electromagnet 7' being thus energized, the armature 10' will be drawn away from the contact point 13' into engagement with the contact 31'. This closes the circuit through the wage-register B and the job-register J' as follows: from the conductor 6, through the

wage-register B, conductor 6, the point 9', switch-blade 10', contact point 31', conductor 17, the tip of the plug b, the tip conductor of the jack 18, conductor 19, job-register J', conductor 20, conductor 15, and back to ground 16^a. As soon, however, as the plug b is withdrawn, the electromagnet 7' is deenergized, and the spring 11' draws the switch-blade 10' against the contact 13', thereby closing the circuit through the wage-register B and the waste-wage register WB, as follows: the conductor 6, wage-register B, conductor 6, point 9', switch-blade 10', contact point 13', conductor 38, wage-register WB, conductor 39, conductor 15, and back to ground at 16^a. 75 70 75 80

It will be clear from the above operation that a workman's wage-register must be actuated simultaneously with either a waste-wage register or a job-register, when a wage-register is automatically disassociated from the other of those two registers. 85

In Fig. 2 I have shown another way in which the electromagnets control the association of the wage-registers with the waste-wage registers or the job-registers. In a way, this arrangement might be considered as a simplification of that shown in Fig. 1, in that it dispenses with one of the contacts, shown in Fig. 1 as associated with each relay. 90 95

Referring to Fig. 2, the winding of the electromagnet 7 is at one end connected with the main conductor 3, through conductor 40, and at its other end is connected by conductor 41 to the sleeve of the plug a. Similarly, one end of the winding of the electromagnet 7' is connected by conductor 42 with the main conductor 3, and at its other end is connected through the conductor 43 with the sleeve of the plug b. From the point 44 of the conductor 45 leads the conductor 46 to the switch-blade or armature 47 of the electromagnet 7. A spring 48 normally holds this armature against the contact 49, which forms the terminal of the conductor 12 leading to the wage-register WA. The conductor 45 is connected to the tip of the plug a. From the point 50 of the conductor 51, which terminates in the tip of the plug b, leads the conductor 52 to the switch-blade or armature 53 of the electromagnet 7'. A spring 54 normally holds this armature against the contact 55, from which leads the conductor 38 to the waste-wage register WB, which is associated with the wage-register B. Considering that the workman assigned to the register A has registered "in", and that he has not been assigned to any particular job, so that his plug a will be in the "out" position, it will be seen that the circuit is closed from the conductor 3 through the wage-register A, the conductor 45, to the point 44, then to conductor 46, the switch-blade 47, contact 49, conductor 12, the waste- 100 105 110 115 120 125 130

wage register WA, conductor 14, conductor 15, and back to the ground at 16a. As soon, however, as the plug *a* is inserted in a job-jack, as would be the case if the workman were assigned to some specific job, the electromagnet 7 would be energized to break the circuit connection with the waste-wage register at the same time that the plug establishes connection with the job-register. In the illustration of Fig. 2, this is the case with the workman assigned to the register B and whose plug *b* has been inserted in the job-jack 18. The insertion of the plug *b* closes the circuit through the associated electromagnet 7' as follows: from the battery 1 to the main conductor 3, to conductor 42, through the winding of the electromagnet 7', conductor 43, the sleeve of the plug *b*, the sleeve contact of the jack 18, conductor 25, conductor 26, conductor 4, and back to the other side of the battery. The electromagnet 7' being thus energized will draw the armature 53 away from the contact 55 and break the circuit through the wage-register WB. At the same time the circuit through the job-register J² is closed as follows: from the conductor 6, through the wage-register B, conductor 51, the tip of the plug *b*, the tip contact of the jack 18, conductor 19, job-register J², conductor 20, conductor 15, and back to the ground at 16a. Thus, precisely the same result is secured as with the arrangement shown in Fig. 1. It will, of course, be evident that those skilled in the art might devise still further modifications as to the precise manner in which the electromagnets for controlling the connections of the wage-registers might be included in the circuit arrangements of my system, without departing from the underlying idea of this invention.

To effect actuation of the registers any suitable form of actuating mechanism may be used. For the sake of illustration, I have shown in Fig. 3 a convenient form of device which may be electrically operated to actuate an associated register. As shown in that figure, a suitable electromagnet 56, adapted to be connected in the energizing circuit of the system, has associated therewith an armature 57, which is carried by the arm or lever 58 pivoted at 59. The pawl 60 pivoted to the lever 58 has engagement with the teeth of the ratchet wheel 61. Whenever the electromagnet is energized it will attract its armature and rock the arm 58 in a clockwise direction. This energization of the electromagnet is more or less only momentary, and as soon as the electromagnet is deenergized the arm 58 will be moved counter-clockwise by the spring 62. During this last mentioned movement of the arm 58 the pawl 60 will move the ratchet wheel 61 the space of one tooth. Upon the next energization of the electromagnet the

pawl 60 will drop into the next lower tooth in order to give the ratchet wheel 61 another one-step advancement upon the deenergization of the electromagnet. This step-by-step movement of the ratchet wheel 61 is communicated to an associated register 63 by any suitable gear connection. In Fig. 3 I have shown the gear 64 rigidly connected with the ratchet wheel 61. The gear 64 meshes with the gear 65, to which is rigidly connected the worm-gear 66. This worm-gear in turn actuates the worm 67 which is mounted upon the driving shaft of the register. Reverse movement of the ratchet wheel 61 is prevented by the locking-dog 68. It will, of course, be understood that the above described form of register-actuating mechanism has been set forth in this case merely for the sake of illustration, this mechanism forming in and of itself no part of my invention, and that any suitable form of device may be used in connection with each register to actuate the same electrically.

It is evident that if it is not desired to show the waste-wages of each individual workman, the register associated with the actuating mechanism may be omitted, suitable means being provided for totalizing the actuations of the electromagnetic mechanisms. A simple form of connection whereby the actuations of the registers—as for instance the waste-wage registers WA and WB, or the job-registers J' and J²—may be totalized is illustrated in Fig. 4, which represents a side view of part of the mechanism shown in Fig. 3.

Referring to Fig. 4, it will be noticed that the ratchet wheel 61 and the gear 64 are combined to form the central member of a differential set, of which the side members are the beveled gears 69 and 70 fixed upon sleeves 69' and 70', respectively. These side members are in engagement with the beveled pinion 71, pivotally mounted in the central member which rotates upon the shaft 72. The sleeves 69' and 70' are also rotatably mounted upon this shaft. At their farther ends these sleeves are provided with beveled gears 73 and 74, respectively, these gears forming each a side member of a differential set which forms part of the actuating mechanism of the next register in the series. These other differential sets have not been shown, for the reason that they are merely a duplication of the differential set, which is shown in Fig. 4, and would therefore be superfluous illustration.

It will be seen from Fig. 4 that the rotation of the central member causes rotation of the beveled pinion 71. If we suppose the sleeve 70' to be stationary, the pinion will impart the actuation of the ratchet wheel 61 to the gear 69 by traveling around the gear 70. If the gear 70 is being actuated by the central member of the associ-

ated mechanism, then the pinion 71 will be rotated at a rate proportional to the sum of the rates of actuation of the ratchet wheels which are operated by the electro-
5 magnets of the two adjacent mechanisms. In this way the actuations of the central members of the various differential sets are ultimately accumulated, to be transferred into a totalizing register, such as the regis-
10 ters WT or JT. With the precise arrangement as shown in Fig. 4, the normal direc-
tion of rotation of the central members of the adjacent differential sets would be alter-
nately in opposite directions, so that the
15 register-actuating mechanisms would have to be arranged accordingly. The differen-
tial totalizing connections which I have shown in Fig. 4 do not in and of themselves form a part of my invention and have been
20 set forth merely for the sake of illustration, and any other means may be provided for totalizing the actuations of certain registers if this is found desirable. However, so far as the operation of my system is concerned,
25 such totalization is not essential. In the modification shown in Fig. 2, I have omitted the totalizing feature in order to promote simplicity in the drawing. I will here state that the register-actuating mechanism shown
30 in Fig. 3 and the differential gear arrange-
ment shown in Fig. 4 are fully set forth in the application of Arthur F. Poole, Serial No. 437,876, filed June 11, 1908.

In the case of the job-registers, it is im-
35 material whether a job-register be associ-
ated with the workman, but it is desirable that the actuations of the mechanisms on a single job at which many individuals may be working should be totalized—as would
40 be shown by the register JT in Fig. 1. It is evident that if there are several jobs on each of which several men may be working, the total for each job may be shown, these totals being again added to show the
45 total wages of the several jobs.

As shown in Fig. 5, the current impulses required to actuate the registers proportionally to the wages paid the workmen, may be produced by the mechanism indicated dia-
50 grammatically which consists in a shaft 77 which has mounted thereon two cam disks 75 and 76. Switch springs 78 and 79 travel in cam grooves formed in the cylindrical surface of the disks and adapted when actu-
55 ated by the cams to make and break contact with the contact springs 80 and 81 respec-
tively. It is apparent that the conformation of the cam grooves determines the number of makes and breaks between the contacts in
60 a given unit of time as the shaft 77 is caused to rotate continuously by any suitable means not shown. The contact springs 78 and 79 are connected together by the wire 82 which is in electrical connection with one ter-
65 minal of the battery 1, the other terminal of

which is grounded. The contact springs 80 and 81 are connected respectively with the wires 6 and 5 extending to the wage registers B and A.

By the above description I do not confine myself to the particular method of accom-
plishing the result herein described, as modi-
fications may be made without departing from the scope of my invention.

What I claim as new and desire to secure by Letters Patent is:

1. In an accounting system, actuating means for a waste-wage register, actuating means for a job-register, a source of electric current adapted to energize said actuating means at a predetermined rate, means for connecting the actuating means of said job-register with said source of current, and means for automatically disconnecting the actuating means of one of said registers from said source on connecting the actuating means of the other register to said source.

2. In an accounting system, a plurality of waste-wage registers, a plurality of job-
90 registers, actuating means for each of said registers, a plurality of sources of electric current adapted to energize said actuating means at predetermined rates, means for connecting the actuating means of any 95 waste-wage register to one of said sources, means for connecting the actuating means of any job-register to the same source, and means for automatically disconnecting or connecting the actuating means of said 100 waste-wage register with said source on connecting or disconnecting respectively the actuating means of said job-register with said source.

3. In an accounting system, a plurality 105 of waste-wage registers, a plurality of job-
registers, an electromagnetic actuating mech-
anism associated with each of said regis-
ters, a plurality of means for delivering elec-
tric impulses of predetermined rates, a 110 switch associated with the actuating mech-
anism of each of said waste-wage registers,
said switch in its normal position adapted
to connect the actuating mechanism of said
waste-wage register with one of said sources 115 of impulses and in its alternate position to
break said connection, an electromagnet as-
sociated with said switch, said electromag-
net when energized adapted to attract said
switch to its alternate position, a source of 120 electric current, means for connecting one
terminal of said electromagnet with said
source of current, a plug associated with
the actuating mechanism of said waste-wage
register, means connecting said plug with 125 said source of electric impulses, independ-
ent means connecting said plug with the
second terminal of said electromagnet, a
jack associated with the actuating mech-
anism of each job-register, means connecting 130

5 said jack with said actuating mechanism, and independent means connecting said jack with said source of current, said plug when inserted in said jack being adapted simultaneously to connect the actuating mechanism of said job-register with said source of impulses and to connect the second terminal of said electromagnet with said source of current, thereby energizing said electromagnet, attracting said switch to its alternate position and disconnecting the actuating mechanism of said waste-wage register from said source of impulses.

10 4. In an accounting system, a plurality of means for delivering electric impulses of predetermined rates, a plurality of waste-wage registers, a plurality of job-registers, an electromagnetic actuating mechanism associated with each of said registers, means 15 for connecting the actuating mechanism of any waste-wage register with one of said sources of impulses, means for connecting the actuating mechanism of any job-register with the same source of impulses, and means 20 for automatically disconnecting the actuating mechanism of said waste-wage register from said source of impulses only during the connection of the actuating mechanism 25 of said job-register with said source of impulses.

30 5. In an accounting system, a plurality of means for delivering electric impulses of predetermined rates, a plurality of waste-wage registers, a plurality of job-registers, an electromagnetic actuating mechanism associated with each of said registers, means 35 for connecting the actuating mechanism of any waste-wage register in series with one of said sources of impulses, means for connecting the actuating mechanism of any job-register in series with the same source of impulses, and means for automatically disconnecting the actuating mechanism of said waste-wage register from said source of impulses only during the connection of the actuating mechanism of said job-register with said source of impulses.

35 6. In a device of the class described, the combination with a source of electric current, of actuating means for a waste-wage register, actuating means for a job-register, means for connecting the actuating means for said waste-wage register to said source of current, means for connecting the actuating means for said job-register to said source of current, and means for automatically disconnecting the actuating means for said waste-wage register from said source of current only during the connection of the actuating means of said job-register to said source.

40 7. In a device of the class described, the combination with a means for delivering electric impulses of a predetermined rate, of electromagnetic actuating means for a

waste-wage register, electromagnetic actuating means for a job-register, means for connecting the actuating means of said waste-wage register to said source of impulses, means for connecting the actuating means of said job-register to said source of impulses, and means for automatically disconnecting the actuating means for said waste-wage register from said source of impulses only during the connection of the actuating means of said job-register to said source of impulses.

45 8. In an accounting system, a means for delivering electric impulses of a predetermined rate, a waste-wage register, a job-register, an electromagnetic actuating mechanism associated with each of said registers, means for connecting the actuating mechanism of said waste-wage register with said source of impulses, means for connecting the actuating mechanism of said job-register with said source of impulses, and means for automatically disconnecting the actuating mechanism of said waste-wage register from said source only during the connection of the actuating mechanism of said job-register with said source.

50 9. In an accounting system, a means for delivering electric impulses of a predetermined rate, a wage-register, a waste-wage register, a job-register, an electromagnetic actuating mechanism associated with each of said registers, means for connecting the actuating mechanism of said wage-register to said source of impulses, means for connecting the actuating mechanism of said job-register with said source of impulses, and means for automatically disconnecting the actuating mechanism of said waste-wage register from said source of impulses only during the connection of the actuating mechanism of said job-register with said source.

55 10. In a device of the class described, the combination with a source of electric current of actuating means for a wage-register, actuating means for a waste-wage register, actuating means for a job-register, means for connecting the actuating means for said waste-wage register to said source of current, means for connecting the actuating means of said job-register to said source of current, and means for automatically disconnecting the actuating means for said waste-wage register from said source of current only during the connection of the actuating means of said job-register to said source.

60 11. In a device of the class described, the combination with a means for delivering electric impulses of a predetermined rate, of electromagnetic actuating means for a wage-register, electromagnetic actuating means for a waste-wage register, electromagnetic actuating means for a job-register, means

for connecting the actuating means of said waste-wage register to said source of impulses, means for connecting the actuating means of said job-register to said source of impulses, and means for automatically disconnecting the actuating means for said waste-wage register from said source of impulses only during the connection of the actuating means of said job-register to said source of impulses.

12. In an accounting system, a means for delivering electric impulses of a predetermined rate, a waste-wage register, a job-register, an electromagnetic mechanism associated with each of said registers, means for connecting the actuating mechanism of said waste-wage register with said source of impulses, means for connecting the actuating mechanism of said job-register with said source of impulses, and an electromagnet associated with the actuating mechanism for said waste-wage register, said electromagnet adapted to break the connection of said waste-wage register with said source of impulses during the connection of said job-register with said source.

13. In an accounting system, a means for delivering electric impulses of a predetermined rate, a waste-wage register, a job-register, an electromagnetic actuating mechanism associated with each of said registers, means for connecting the actuating mechanism of said waste-wage register with said source of impulses, means for connecting the actuating mechanism of said job-register with said source of impulses, an electromagnet associated with said waste-wage register, and means for energizing said electromagnet during the connection of said job-register with said source, said electromagnet when energized adapted to break the connection of said waste-wage register with said source.

14. In an accounting system, a means for delivering electric impulses of a predetermined rate, a waste-wage register, a job-register, an electromagnetic actuating mechanism associated with each of said registers, means for connecting the actuating mechanism of said waste-wage register to said source of impulses, means for connecting the actuating mechanism of said job-register with said source of impulses, a switch associated with the actuating mechanism for said waste-wage register, said switch in its alternate position adapted to break the connection of said actuating means with said source of impulses, an electromagnet adapted to attract said switch to its alternate position, and means for energizing said electromagnet during the connection of the actuating means of said job-register to said source of impulses.

15. In an accounting system, a means for delivering electric impulses of a predeter-

mined rate, a waste-wage register, a job-register, an electromagnetic actuating mechanism associated with each of said registers, means for connecting the actuating mechanism of said waste-wage register to said source of impulses, means for connecting the actuating mechanism of said job-register with said source of impulses, a switch associated with the actuating mechanism for said waste-wage register, said switch in its alternate position adapted to break the connection of said actuating means with adapted to attract said switch to its alternate position, and means for connecting the actuating means of said job-register to said source of impulses during the energization of said electromagnet.

16. In a device of the class described, a wage-register, a waste-wage register, a job-register, an electro-magnetic actuating mechanism for each of said registers, a means for delivering electric impulses of a predetermined rate, means for permanently connecting the actuating mechanism of said wage-register with said source of impulses, means for connecting the actuating mechanism of said waste-wage register to said source of impulses, means for connecting the actuating mechanism of said job-register to said source of impulses, a switch associated with the actuating mechanism for said waste-wage register, said switch in its normal position adapted to complete the connection of the actuating mechanism of said waste-wage register with said source of impulses and in its alternate position to complete the connection of the actuating mechanism of said job-register with said source of impulses, an electromagnet adapted to attract said switch to its alternate position, and means for energizing said electromagnet.

17. In a device of the class described, a wage-register, a waste-wage register, a job-register, an electro-magnetic actuating mechanism associated with each of said registers, a means for delivering electric impulses of a predetermined rate, means for connecting the actuating mechanism of each register to said source of impulses, and means for selectively breaking the connection of either the actuating mechanism for said waste-wage register or the actuating mechanism for said job-register with said source of impulses.

18. In a device of the class described, a wage-register, a waste-wage register, a job-register, an electromagnetic actuating mechanism associated with each of said registers, a means for delivering electric impulses of a predetermined rate, means for connecting the actuating mechanism of each register to said source of impulses, a switch for breaking the connection of either the actuating mechanism for said waste-wage or said job-

- register with said source of impulses, an electromagnet, means for energizing said electromagnet, said electromagnet when energized adapted to attract said switch and when not energized to allow said switch to resume its normal position.
19. In an accounting system, a means for delivering electric impulses of a predetermined rate, a wage-register, a waste-wage register, a job-register, an electromagnetic actuating mechanism associated with each register, means for connecting each of said actuating mechanisms with said source of impulses, and means for disconnecting the actuating mechanism of the waste-wage register from said source and connecting the actuating mechanism of the job-register with said source by a single operation.
20. In a device of the class described, the combination of a source of electric impulses, a waste-wage register, a job-register, actuating mechanism for each of said registers, means for connecting said actuating mechanisms with said source, and means for disconnecting the actuating mechanism of the waste-wage register from said source and connecting the actuating mechanism of the job-register with said source by a single operation.
21. In a device of the class described, the combination of a pair of registers, an electromagnetic actuating mechanism associated with each register, a source of electric impulses, connections between said source and said mechanisms for actuating the registers, and means for disconnecting the actuating mechanism of one of said registers from said source and automatically connecting the actuating mechanism of the other register with said source by a single operation.
22. In a device of the class described, the combination of a pair of registers, an electromagnetic actuating mechanism associated with each register, a source of electric impulses, and connections between said source and said mechanism for actuating the registers, said connections including a jack and a coöperating plug, whereby the insertion of the plug into the jack automatically disconnects the actuating mechanism of one of the registers and connects the actuating mechanism of the other register.
23. In a device of the class described, the combination of a waste-wage register, a job-register, electromagnetic actuating mechanism associated with each register, a source of electric impulses, and connections between said source and said mechanism for actuating the registers, said connections including a jack and a coöperating plug, whereby the insertion of the plug into the jack automatically disconnects the actuating mechanism of one of the registers and connects the actuating mechanism of the other register.
24. In an accounting system, the combination of a plurality of registers, an electric circuit switching mechanism for including a desired one of such registers in said circuit, and electromagnetic register connecting mechanism made operative by interrupting the circuit through the switching mechanism.
25. In an accounting system, the combination of a plurality of registers, an electric circuit switching mechanism for including a desired one of such registers in said circuit, electromagnetic register connecting mechanism made operative by interrupting the circuit through the switching mechanism and inoperative by establishing the circuit through such switching mechanism.
26. In an accounting system, the combination of two registers, an electromagnetic device actuated by placing a first one of said registers in operative condition, and mechanism controlled by said electromagnet for placing the other of said registers in operative condition when said first register is placed in inoperative condition.
27. In an accounting system, the combination of two registers, an electromagnetic device actuated by placing a first one of said registers in operative condition, and mechanism controlled by said electromagnet for placing the other of said registers in operative condition when said first register is placed in inoperative condition, and for placing said other register in inoperative condition when said first register is placed in operative condition.

In witness whereof, I hereunto subscribe my name this 9th day of February A. D. 1909.

LYNN A. WILLIAMS.

Witnesses:

HENRY M. HUXLEY,
CHARLES J. SCHMIDT.
